CLAIM

The ornamental design for a display shelf for model vehicles, as shown and described.

DESCRIPTION

FIG. 1 is a perspective top, front and left side view of a display shelf for model vehicles showing my new design;
FIG. 2 is a front view thereof;
FIG. 3 is a rear view thereof;
FIG. 4 is a top view thereof;
FIG. 5 is a side view thereof; and,
FIG. 6 is a right side view thereof.

The broken-line disclosure of model cars, of nominative printing characters and of street lamps in the views of FIGS. 1 to 6 is for illustrative purposes only and forms no part of the claimed design.
